ABSTRACT OF THE DISCLOSURE

A scraper including a main body and a harness secured thereto, wherein the harness may be adjustably secured to the main body to vary the digging angles thereof.

This invention relates to a slushing scraper and more particularly to a slushing scraper commonly operated by a line.

Slushing scrapers are employed to handle a wide range of materials such as ore, coal and earth under severe operating conditions as found in excavating, mining, construction, and grading, either above ground or below ground. Thus, the nature of material moved by the scraper varies considerably from mine to mine or from excavation to excavation as does the environment in which the scraper is used.

The scraper is connected to a line and pulled in one direction across the body of ore or the like with the lower blade portion of the scraper scooping material into the interior of the scraper and the scraper riding across the load after having been filled. The scraper is returned to digging location by a return line connected to the rear of the scraper.

The conventional scraper has a main body portion with a bottom digging blade and a back wall leading to generally short side walls forming a bucket-like cavity in which is gathered the material. Secured to the main body are yoke arms, sometimes called a harness, which extend forwardly from the main body and are joined together at a forward location. The in-haul cable is usually attached either to a forward point on the yoke or to the main body of the scraper. The yoke arms are rigidly secured to the main body at a fixed angle. When the cable is pulled, the yoke assumes the plane of the cable and the main body tilts to a digging angle of approximately 44 to 50 degrees to dig into the load to fill the scraper.

With the prior art scrapers, the orientation of the yoke to the main body was fixed and the relationship of the scraper to the in-haul cable was fixed. These fixed relationships have imposed limitations in obtaining the correct digging angle for various operating conditions and thereby has limited efficient performance. Accordingly, an object of the present invention is to eliminate the foregoing limitations by constructing a variable pitch type of scraper which can be adjusted to afford different digging angles for different operating conditions.

Another object of the invention is to secure a scraper yoke in one of a plurality of positions relative to the main scraper body to change the orientation of the yoke to the main body, enabling a more efficient scraping operation to be realized.

A further object of the invention is to be able to change the inclination of the main body portion of a scraper to its attached in-haul line to achieve an efficient digging angle for the scraper.

Another object of the invention is to guide the cable at spaced forward and rearward locations on the scraper in the general plane of the yoke so that adjustments in position of the main body relative to yoke result in ad-

2

justments of the scraper blade angle relative to the in-haul cable.

5 A further object of the invention is a new and improved scraper of a novel construction including a straight transverse scraper blade portion and rounded or crescent back wall portion.

Other and further objects of the present invention will be apparent from the following description and claims and are illustrated in the accompanying drawings which, by way of illustration, shows preferred embodiments of the present invention and the principles thereof and what is now considered to be the best mode contemplated for applying these principles. Other embodiments of the invention embodying the same or equivalent principles may be used and structural changes may be made as desired by those skilled in the art without departing from the present invention and the purview of the appended claims.

In the drawings:

20 FIG. 1 is a plan view of a scraper constructed in accordance with the preferred embodiment of the present invention;

FIG. 2 is a partial sectional view of the scraper of FIG. 1;

25 FIG. 3 illustrates another embodiment of the invention wherein a cable is attached to a central brace member;

FIG. 4 is a plan view of the cable attachment to the central brace member of FIG. 3;

30 FIG. 5 is another embodiment of the invention wherein yoke arms are separate from one another and are joined by a bushing;

FIG. 6 is a sectional view taken along the line 6—6 of FIG. 5 showing the bushing; and

35 FIG. 7 is a sectional view taken along the line 7—7 of FIG. 5 and in the direction of the arrows showing the bushing, yoke arms and shoe.

40 Referring now to the drawings and more particularly to FIG. 1, there is illustrated a scraper bucket 10 including a main body portion 11 with a yoke 12 extending forwardly from the main body portion 11 to a yoke head or forward portion 14 through which is guided a line or cable 15, which is secured to the main body portion 11 by a pin 16.

45 The main body portion 11 of the scraper 10 is a casting of manganese steel or the like having a curved back wall 18 of a generally crescent shape extending between opposite integral side walls 19. The main body portion 18 also includes an integral and downwardly inclined lip portion or bottom wall 20, FIG. 2, to which is secured 50 separable teeth 22 and 23. Also, integrally formed with the back wall 18 is an overhead or top wall 25, which extends forwardly and over the cavity formed between the respective side walls 19 and back wall 18.

55 When the scraper 10 is being moved in the in-haul direction by a force pulling on the cable 15, the scraper 10 assumes a digging angle A (FIG. 2, solid lines) so that the front blade portion 22 and 23 dig into the load and scoop the material rearwardly along the inclined wall portion 20 toward the crescent shape back wall 18. As the blades 22 and 23 dig deeper into the load and as the scraper cavity becomes filled, the material fills the scraper cavity and presses against the under surface 28, FIG. 2, of the top wall 25 to exert a lifting force on the scraper 10 preventing the digging of the scraper blades 22 and 23 deeper into the load. Thus, the scraper 10 rides the load when the scraper cavity is full and the scraper 10 is being pulled across the load.

60 The slushing scraper 10 is employed under a wide variety of operating environments for handling a number of different types of material of various sizes. Typical uses for scrapers are excavating, mining, construction, and grading. Also the type and size of the material being

transported vary considerably. Heretofore, scrapers have had the yokes secured to the main body portions so that only one angular relationship or pitch existed between the yoke and the main body portion. These prior art scrapers had only a single digging angle (i.e., angle of the scraper blade to the load during the insertion of the scraper blade into the load). The efficiency of the scraper was limited, particularly where a single scraper would be used for a number of different operating environments, in that the particular digging angle for the greatest efficiency for a given operating environment was not always available.

An important aspect of the present invention is the provision of a variable pitch or angular relationship between the yoke 12 and the main body portion 11 and an adjustable digging angle so that the digging angle may be adjusted to the particular need of the operating conditions. For this purpose, the yoke 12 includes a pair of yoke arms 30 and 31, which are pivotally secured by pivot pins 32 to the side walls 19 of the main body portion 11. It is preferred to hold the yoke 12 at each of its fixed angular positions relative to the main scraper body 11 by means of a central brace 35. The brace 35 has an apertured end 37, FIG. 1, secured to the yoke 12 by a pin 36 and is secured to the main body portion 11 by a securing means 38 including a pin 39 inserted between the bifurcated arms 40 and 41 of the central brace 35.

The digging angle A, FIG. 2, is adapted to be adjusted between a number of positions, which are generally indicated by the dotted line positions of the digging blade 22 in FIG. 2. The digging angle A of FIG. 2 is that angle between the digging blade 22 and the horizontal plane PL which is the plane of the load. Manifestly, the plane PL of the load is often inclined to the horizontal for such piles, excavations and the like.

In the embodiment of the invention illustrated in FIG. 1, the yoke 12 is a one-piece structure with the arms 30 and 31 integrally united to each other and to the head portion 14 of the yoke 12. The head portion 14 of the yoke 12 includes a central and cylindrical body 45 having a central bore, FIG. 2, through which extends the cable 15. The cylindrical body 45 receives a cable guide bushing 46, FIG. 2, which is an integral portion of a front shoe 48.

Extending outwardly from the cylindrical body 45 and secured on opposite sides thereof are wing-like walls 49 and 50 which are reinforced by vertical cast stiffener ribs 51, 52, 53 and 54, respectively. A pair of rearwardly extending lugs 57 and 58, FIG. 1, are formed at the rear portion of the yoke head 14 and are apertured to receive the retaining pin 36, which is inserted through apertures in the lugs 57 and 58 and an aperture in the forward end 60 of the center brace 35. The pin 36 has an enlarged head 36A and a washer 36B held by a cotter key 36C in lieu of a bolt, which is often difficult to remove.

Likewise, in lieu of a bolt, the shoe 48 is secured to the yoke head 14 by means of a tapered wedge 62, which extends through a keyway slot 66 formed in the lower wall of the cylindrical body 45, FIG. 2. The tapered wedge 62 has a large head portion 63 tapering into a bendable arm 64, bent over, FIG. 1, to hold the wedge 62 against displacement in a well known manner. As best seen in FIG. 2, the wedge 62 fits within the shouldered keyway slot 66 formed in the lower portion of the forward cylindrical wall 45 and in an opposed matching keyway slot 67 formed by the lower portion of the circular wall 70 of the shoe 48.

The shoe 48 is a separable casting with its cable guide bushing 46 split into spaced portions 71 and 72. When removing the shoe 48, the wedge 62 is removed and the shoe 48 is driven leftwardly relative to the yoke head 14, as seen in FIG. 2, to slide its forward guide bushing portion 72 into the space 74 and to slide the front cable bushing portion 71 leftwardly past an end wall 75 of the yoke head 14. Thus, the shoe 48 can be moved downwardly to remove the rear cable guide 71 from the posi-

tion in the space 74 in the yoke head 14. Manifestly, a reversal of the above operation is made to secure the shoe 48 to the yoke head 14.

When the scraper 10 is pulled rightwardly, as viewed in FIGS. 1 and 2, during a return-haul, the sloping surface 78 on the shoe 48 will be riding along the bottom surface of the trough with the blades 22 and 23 riding along their respective rearward surfaces 81.

The in-haul cable 15 is threaded through the flared surface 82 of the forward cable guide bushing portion 71 of the shoe 48 and through the rearward bushing portion 72 and beneath the connecting pin 36 in central brace 35. The cable 15 has a connector 83 at its end secured by the pin 16 to bifurcated arms 85 and 86 integrally formed on the upper plate 25 of the scraper body 11.

For the purpose of connecting the central brace 35 to the main scraper body 11, the bifurcated arms 40 and 41 of the central brace 35 have aligned apertures 88 for receiving the connecting pin 39, which is also disposed through one of a pair of openings 92 and 93 in an insert 94, FIG. 2, in the integrally cast lug 90 on the upper body plate 25. To align the pin 39 with one of the holes 92 or 93 in the insert 94, the yoke arms 30 and 31 are pivoted about their pivot pins 32 in the clockwise or counterclockwise direction. The insert 94 is sector-shaped and is seated in a complementary shaped seat 95 in the lug 90.

Preferably, the insert 94 has its pin-receiving holes 92 and 93 asymmetrically located on the symmetrically-shaped insert 94, such that the removal and reversal of the insert 94 causes the realignment of the holes 92 and 93 therein from the positions previously occupied. Thus, each of the holes 92 and 93 is adapted to have two distinct positions or locations such that when the pin 39 is inserted therethrough the inclination of the yoke arms 30 and 31 is thereby changed. The use of the insert 94 permits the plurality of close-spaced pin locations with a thicker insert wall between the holes 92 and 93 than could be afforded by drilling four separate holes slightly offset from one another. Thus, the insert 94 provides a plurality of positive pin-receiving locations in a relatively small space.

Another important aspect of the present invention is the geometrical shape or configuration of the main scraper body 11. As can be understood from FIGS. 1 and 2, the scraper blades or teeth 22 and 23 have front edges 100 and 101, which extend in a straight line, as seen in FIG. 1, while the inner surface 102 of the back wall 18 is curved in a crescent or concave curvature. The crescent curvature of the back wall 18 is more effective than the conventional straight, back wall of the prior art scrapers in holding material between the side walls 18 and 19 and within the scraper 10 as the scraper is being pulled along by the in-haul cable 15.

The straight digging edge formed by the front edges 100 and 101 of the scraper blades 22 and 23 being aligned in the same plane has the advantage of preventing the digging in of the corner blades 22 as contrasted to scrapers having a curved digging blade. That is, where the angle of the pulling cable was not held constant, any lifting or lowering of the yoke arms tilted the curved, prior art, scraper blade and cause the curved blade to dig into the load permitting the load to slip out of the scraper at the center thereof.

Thus, the present scraper 10 has a straight digging blade to prevent such digging in at a corner and has a crescent or curve shape to back wall 18 to afford a greater capacity and a better holding of the material before and within the scraper 10.

After the scraper 10 has been moved by the in-haul cable in the forward direction to transport the material, the scraper is returned by return cables (not shown) secured to one or more of the integrally formed lugs 110, 111 and 112, which are apertured for receiving a shackle connection to the return-haul cable or cables. The lugs 110, 111 and 112 are spaced along the back wall 18 to afford a balance pulling during the return of the scraper 10.

In the embodiment of the invention described hereinbefore in conjunction with FIGS. 1 and 2, the in-haul cable 15 is secured by the pin 16 to the bifurcated lugs 85 and 86 inwardly formed on the top plate 25 of the scraper body 11. However, in another embodiment of the invention, the cable 15 is attached directly to the center brace 35 by a pin 16A, FIGS. 3 and 4. In the embodiment shown in FIGS. 3 and 4, the cable 15 is guided through a bushing 46 and the yoke head 14 and beneath the pin 36 to the pin 16A secured to the bifurcated arms 40 and 41 of the central brace 35.

The yoke 12, or harness as it is sometimes called, acts as a bumper to guide the scraper about corners or obstruction points and is generally at least as wide as the distance between side scraper walls 19. In many locations, such as underground mines, the use of a one-piece yoke, renders the handling, installation and assembly of the scraper 10 difficult and it is preferred to employ a two-piece yoke. A two-piece yoke 120 is illustrated in FIGS. 5, 6 and 7, and includes a pair of yoke arms 121 and 122 secured to one another by a combined bushing and fastener 125, FIG. 6. The yoke arms 121 and 133 each terminate in a pair of interfitting lugs or projections 126 and 127, respectively. Each of the interfitting lugs 126 has a central aperture 130 sized to accept the cylindrical body 132 of the combined bushing and fastener 125, FIG. 6. As shown in FIG. 6, the cylindrical body 132 has a flanged outer head 134 adapted for flush engagement with an upstanding wall 135 of a shoe 136. The opposite end of the combined bushing and fastener 125 has a threaded end portion 138 on which is threaded a fastener 139. The fastener 139 bears against another upstanding wall 140 of the shoe 136.

The shoe 136 includes a lower depending portion 145 with an inclined riding face 146 adapted to ride along the load during the return-haul of the scraper 10. As best seen in cross section in FIG. 7, the body 145 of the shoe 136 has a transverse wall 148 disposed to engage vertical, scraper arm flange 149 and to engage opposed fingers 126 and 127 of the scraper arms 121 and 122.

Each of the yoke arms 122 and 121 has a boss 150 which is apertured at 151 to receive the pin 36 for attaching a center brace 35. The respective arms 121 and 122 are also provided with flange or wing portions 154 which on the other side thereof have reinforcing ribs 155 extending at right angles thereto. A V-shaped, central reinforcing body flange 157 is provided on each yoke arm 121 and 122 with vertical surfaces 158 meeting along a central meeting line when the yoke arms 121 and 122 are joined by the bushing 125.

The respective pins 16, 16A, 32 and 39 each have an enlarged head and an aperture at the thermal end for receiving a cotter key or the like rather than having threaded ends for nuts which may become loosened and then allow the surfaces of the joined areas to be worn. Also, the removal of the nuts is often extremely difficult because of thread clogging and damage to the threads thereby necessitating cutting or burning off of the bolts and nuts. Thus, it is preferred that the threaded bolts be eliminated although the present invention is not limited to any particular pin or bolt fastener.

From the foregoing, it will be seen that the present invention affords a universal scraper which is adjustable to provide efficient digging angle from a plurality of digging angles to which the scraper may be adjusted. Preferably, adjustment of the digging angle is accomplished by changing the angular relationship of the bail with respect to the main scraper body. Preferably, the arms and body are locked in the preferred digging angle against angular movement. Also the cable is guided through the yoke arms and attached at a rearward location either to the body or the yoke so as to establish a pulling force or line through the yoke about which the body portion may be pivoted to change the digging angle.

Hence, while preferred embodiments of the invention

have been described and illustrated, it is to be understood that they are capable of variation and modification.

I claim:

1. In a scraper adapted to be attached to a digging cable, a main body means including blade means at the lower portion of said main body means for scooping material, bottom, top and side walls on said main body means defining a central material receiving cavity, yoke arm means secured to said main body means and extending above said digging blade means and forwardly thereof, means pivotally mounting said yoke arm means on said main body means, yoke head means at the forward portion of said yoke arm means, bushing means in said yoke head means for receiving and guiding said digging cable, central brace means extending between said yoke head means and said main body means and having an aperture therein, means on said main body means for attaching said cable thereto, securing means on said main body means having a plurality of apertures therein for alignment with the aperture on said central brace means, and pin means disposed through an aperture on said securing means on said main body means and the aperture in said central brace means to lock said arm means in one of a plurality of positions relative to said main body means.
2. The scraper of claim 1 wherein said securing means includes an insert having a plurality of apertures therein, said insert means adapted to be turned and re-oriented in a cavity in said main body means to re-align its apertures with respect to said main body means.

3. The scraper of claim 1 wherein said arm means includes a pair of separate yoke arms secured together at said yoke head means.

4. The scraper of claim 3 wherein said separate yoke arms are secured together by a combined bushing and securing means.

5. In a scraper adapted to be attached to a digging cable, a main body means including blade means at the lower portion of said main body means for scooping material into a central cavity in said main body means, separate yoke arm means secured to said main body means and extending above said digging blade and forwardly thereof, means pivotally mounting each of said yoke arm means on said main body means, interfitting finger portions on the forward portions of each of said yoke arm means, combined bushing and securing means securing said interfitting finger portions together to form a yoke head of said interfitting finger portions, said combined bushing and securing means having a hollow bore for guiding said cable, means on said main body means for securing said cable thereto, and securing means on said main body means for securing said arm means in a plurality of angular positions relative to said main body means.

6. In a scraper adapted to be attached to a digging cable, a main body means including blade means at the lower portion of said main body means for scooping material into a central cavity formed in said main body means, yoke arm means secured to said main body means and extending above said digging blade and forwardly thereof, means pivotally mounting said yoke arm means on said main body means, yoke head means at the forward portion of said yoke arm means, bushing means in said yoke head means for receiving and guiding said digging cable, a center brace means extending between said yoke head means and an upper wall of said main body means, means on said main body means for attaching said cable thereto, securing means on said main body means to lock said arm means in one of a plurality of positions relative to said main body means; and a shoe means secured to said yoke arm and having a central bore through which passes the digging cable.

7. A scrapper as defined in claim 6, wherein said main body means includes a rear wall and short side walls, said rearwall having its interior surface of a concave curvature transversely between said side walls, and

said blade means including a digging edge extending in a substantially straight line between said short side walls.
